UNITED STATES PATENT OFFICE.

LOUIS P. FOSNOT, OF READING, PENNSYLVANIA, ASSIGNOR, BY MESNE ASSIGNMENTS, TO READING STANDARD COMPANY, A CORPORATION OF PENNSYLVANIA.

CARBURETER FOR EXPLOSIVE-ENGINES.

No. 908,764.

Specification of Letters Patent.

Patented Jan. 5, 1909.

Application filed September 13, 1906. Serial No. 334,368.

To all whom it may concern:

Be it known that I, LOUIS P. FOSNOT, a citizen of the United States, and a resident of the city of Reading, in the county of Berks and State of Pennsylvania, have invented certain new and useful Improvements in Carburetors for Explosive-Engines, of which the following is a specification.

My invention relates particularly to carbureters adapted for motor cycle use, and it consists in certain improvements in construction hereinafter fully described in connection with the accompanying drawings and the novel features of which are specifically pointed out in the claims.

Figure 1 is a partly sectional elevation of a carbureter embodying my invention in preferred form, the section being taken on the line 1—1 of Figs. 2 and 4. Fig. 2 is a plan view of the same. Fig. 3 is a partly sectional elevation taken on the line 3—3 of Figs. 2 and 4. Fig. 4 is a sectional plan view taken on the line 4—4 of Figs. 1 and 3. Fig. 5 indicates a modified construction in sectional elevation.

An ordinary spraying device for gasolene or other hydrocarbon liquid, is indicated at 5, located in a central tube 6 of the carbureter and communicating through suitable 30 conduits 7, 8, with a gasolene chamber 9. In the preferred construction shown this central tube 6 rises from a perforated or spoked plate 10 which screws into the lower end of the mixing chamber cylinder hereinafter described, and it is loosely surrounded by a partition ring 11 carried by said plate 10. This partition ring forms an annular outer air-chamber 12 and an annular inner air-chamber 13 both communicating with a 40 lower air-inlet chamber 14 which is carried by a depending extension 15 of the central tube 6.

The mixing chamber cylinder as shown is formed by a lower main portion 20 and an 45 upper outlet portion 21, the former of which is provided with a vertically movable cylindrical cut-off valve 22 in addition to the sprayer 5 and partition ring 11 already mentioned, while the latter is provided with 50 a rotary cylindrical throttle valve 23 arranged to regulate the volume of fuel gas discharged through the side outlet 24 therefrom. The particular construction and co-operative arrangement of these parts are as 55 follows: The cylindrical cut-off valve 22,

which slidably fits in cylinder 20, has its lower circular edge 25 arranged to seat upon the cone-shaped top portion 26 of the partition ring 11 so as to cut off the upward flow of air through the outer annular passage 12 60 excepting as such additional supply of air is called for to provide the increased amount of fuel-gas discharged through the outlet 24 when the throttle valve 23 is opened for heavier work than the normal. This opening movement of the vertically sliding cut-off valve 22 is effected coincidently with the opening of the rotary throttle valve 23, by means of a central rod 30 connecting the two valves. The throttle valve 23 is provided 70 with a stem 31 secured to the valve head 32 and extending through a cap 33 on the mixing chamber cylinder 21; the projecting stem having a handle 34 suitably fixed thereto for convenient handling by the operator. 75 The central connecting rod 30 is fixedly attached at its lower end to the open head 36 of the cylindrical cut-off valve 22, and extends upward into the rotary throttle valve 23, with which it is operatively connected by 80 means of a loose transverse pin 37 inserted in the hollow head 38 of the rod 30; the projecting ends of said pin being arranged in engagement with the oblique slots 39 formed in the cylindrical wall of the throttle valve 85 23, so that the rotary movement of the latter required to properly increase the portion of wall port 40 registering with the side outlet 24 from the mixing chamber, will correspondingly effect the lifting of the air cut-off 90 valve 22. The latter is vertically guided in the cylinder 20 by means of a lateral projection 41 engaging a vertical wall slot 42, so as to be incapable of rotary movement.

The gasolene chamber 9, as shown, is an 95 annular chamber surrounding the mixing cylinder 20 and formed integral therewith, the separately formed upper cylindrical portion 21 being secured to the lower cylindrical portion 20 by means of a bolting flange 45 100 arranged to cover said gasolene chamber.

The supply of gasolene to the chamber 9 is controlled as usual by a needle valve 50. This valve as shown is mounted in a vertical conduit 51, connected to a supply tube 52 105 and communicating at 53 with the chamber 9. To provide for nicely adjusting this valve its point is seated in a ring 54 which is adjustable vertically in a screw-threaded portion of the conduit 51, while the upper por- 110

tion of its stem is guided in a screw-cap 55 and its vertical lift is regulated by an adjusting screw 56 as indicated. To provide for the automatic opening and closing of the 5 valve as required I employ a lever 60 pivoted intermediately at 61 and having its short end 62 engaging the stem of the valve while its semi-circular inner portion is carried half way around the mixing cylinder 20 10 and has its ends 63 arranged to contact with an annular float 64 in the gasoline chamber 9 so as to be lifted by the latter when said chamber is properly filled, and thereby closing the needle valve which is normally held 15 open by said lever.

In the modified construction indicated in Fig. 5, the rotary throttle valve 70 in the upper portion of the mixing cylinder, is arranged to be rotated upon a horizontal axis 20 71, instead of a vertical axis as in the preferred construction previously described; the vertically moving cylindrical cut-off valve 72 however being coincidentally adjusted as before to regulate the air inlet 25 around the conical partition 73, by means of a lifting cam 74 and a depressing spring 75. Instead of locating the gasoline chamber around the mixing cylinder, it is in this case shown to one side thereof and the needle 30 valve mechanism described is located centrally in said chamber.

What I claim is:—

1. In a carbureter having a cylindrical mixing chamber with side outlet near one end thereof, and a central hydrocarbon inlet 35 and an air inlet chamber surrounding the same at the other end, a hollow conical partition in said air-inlet chamber, a cylindrical air cut-off valve in said mixing chamber seating on said conical partition, and a separately formed and independently mounted throttle-valve for said outlet operatively connected to said cut-off valve substantially as set forth.

2. In a carbureter having a cylindrical 45 mixing chamber with side outlet near one end thereof, and a central hydrocarbon inlet and an air inlet chamber surrounding the same at the other end, a hollow conical partition in said air-inlet chamber, a vertically 50 movable cylindrical air cut-off valve in said chamber seating on said conical partition, and a rotary cylindrical throttle valve for said outlet operatively connected to said cut-off valve substantially as set forth.

In testimony whereof, I affix my signature, in the presence of two witnesses.

LOUIS P. FOSNOT.
